UNITED STATES PATENT OFFICE.

WILLIAM BLACKWELL COWELL, OF CATFORD, ENGLAND.

APPARATUS FOR USE WHEN PAVING ROADS AND THE LIKE.

1,157,297.

Specification of Letters Patent.

Patented Oct. 19, 1915.

Application filed March 15, 1915. Serial No. 14,412.

To all whom it may concern:

Be it known that I, WILLIAM BLACKWELL COWELL, a subject of the King of Great Britain, and resident of No. 28 Berlin road, Catford, in the county of Kent, England, have 5 invented new and useful Apparatus for Use when Paving Roads and the like, of which the following is a specification.

One object of this invention is to enable 10 a more uniform heating or drying of the road to be obtained and for this purpose the heater is provided with a diaphragm between the source of heat and the road surface, such diaphragm being made of iron, 15 earthenware, or other material of such a nature and dimensions or weight as to be capable of absorbing and giving off to the road a considerable amount of heat. This diaphragm may or may not be perforated, but 20 in any event it must not be possible for any flame to come into direct contact with the road.

Another object is to avoid overheating of 25 the material such as asphalt or other fusible material, already placed on the road and which, when melted, is adapted to form a binding material or road surface and moreover, it is essential that the diaphragm should not be injured, coated or clogged by 30 coming into contact with such road-binding or road surface forming material as that would cause the efficiency of the diaphragm to be impaired and would certainly have the effect of burning a certain portion of the material referred to. For these purposes the 35 diaphragm is supported at least a little distance above the lower edge or base of the heater or desiccator.

A further object of the invention is to 40 avoid undue and useless cooling of the heat absorbing and distributing diaphragm, particularly when a perforated diaphragm is used. For this purpose, the box forming the desiccator is made as shallow as possible, so 45 that there shall only be a very limited air space above the heat absorbing diaphragm. In order to allow of the insertion of heaters into the apparatus, the top of the shallow box increases in depth toward the middle, by, 50 for example, making the top in the form of a shallow truncated pyramid. In this way the roof or top of the box is kept as near as possible to the heat absorbing diaphragm so that the heat in the latter is conserved and 55 can only be radiated to the road surface and moreover, when oil burners are used, they are so arranged that their flames are caused to play angularly onto the diaphragm and the latter does not thus tend to be overheated in places, the heat is conserved and can only 60 be radiated to the road surface.

The invention therefore provides a road heater or desiccator comprising a shallow box, having an open bottom, a diaphragm capable of absorbing heat and situated a 65 little above the basal edges of the box, a roof or top, low down over such diaphragm and of a form rising toward the middle to allow for the uniform distribution of a hot blast centrally supplied, or so that while 70 allowing for the insertion of heaters such as blow lamps, the air space above the diaphragm is kept as small as possible.

In order to enable the invention to be readily understood reference is directed to 75 the accompanying drawings in which:—

Figure 1 is a view partly in section and partly in elevation of one construction of desiccator, and, Fig. 2 is a part sectional plan view of such desiccator and, Fig. 3 is 80 a detail view in elevation illustrating a form of removable handle for use in lifting the desiccator.

According to the construction shown in 85 Figs. 1 and 2, the desiccator consists of an oblong rectangular framework *a* of T iron or angle iron or metal of other appropriate cross-section, the length of which may be about six feet three inches with a width of three feet three inches. The sides are suitably about four inches high, but obviously these dimensions may be departed from if desired. This framework *a* is covered at 90 the sides by sheet iron or the sides may be formed of thin angle iron entirely. Two opposite sides *b* and *c* are suitably connected at the top by a number of parallel pieces *d* of T iron fixed in position with their horizontal members below to form racks to receive a number of unperforated or as shown, 100 perforated plates *e* of metal or earthenware which rest on the horizontal flanges of the members *d*. The plates are suitably prevented from falling out in case the desiccator be stood on end or inverted, by screws, 105 bolts, clips or in any other convenient manner not shown. The top or roof of the desiccator, which extends to a height of about one foot, is suitably made to slope downward from the center toward the four sides, 110 or it may be arched, and in the construction shown in the drawings it is covered with

sheet iron in the form of more or less triangular plates f , f' , supported by T iron or angle iron members g connected or secured at the upper end to a ring, or, as shown, a perforated rectangular plate h . The side plates or covers f and also the end plates or covers f' if required may be removable in order to allow access to the interior of the desiccator. The top and sides may be lagged 10 with asbestos or other suitable non-conducting material to prevent escape of heat and a pipe k may be passed through the central opening in the plate h into the interior of the desiccator for the purpose of admitting 15 hot air or gas. To improve the distribution of the hot air or the like to all parts of the desiccator, the pipe k is closed at the bottom and provided with a number of perforations l , as shown, spaced at suitable distances 20 apart. The pipe k is provided with a union or coupling m outside of the top of the desiccator for connection to another pipe or hose n for conveying the hot air or gas to the desiccator. Also, if required, or in addition 25 to the pipe k which in the latter case may be provided with a plug cock or valve, the top of the desiccator may be furnished with a door or doors in any convenient position to cover the openings or holes for the insertion 30 of a blow-lamp or lamps or the like to be used instead of a supply of hot air or gas delivered from the outside by the pipe k . As shown in Figs. 1 and 2, the blow lamp or lamps o may be mounted upon brackets o' 35 supported outside of the desiccator upon the end plates f' and be arranged to deliver in each case a flame or flames into the interior of the desiccator through holes p or it may be through nozzles of suitable construction 40 inserted in the holes, and if desired to induce a supply of fresh air sufficient to maintain combustion. Moreover, a supply of air under pressure may also be maintained at the same time through the perforated pipe 45 k . The desiccator is suitably provided with T iron corner pieces q , one flange of each of which pieces extends transversely beyond the sides of the desiccator and these flanges are slotted at r so as to allow of the passage 50 of rods s for the purpose of lifting the desiccator from place to place, or the rods s may be reduced at the ends as shown in Fig. 55 to receive bent handles t , so as to thus enable workmen to lift the desiccator from place to place, as will be readily understood.

I claim:—

1. An apparatus for drying and heating the surface of, or material laid on, a road or road foundation, comprising a shallow box 60 inclosed on all sides, having an open bottom, a diaphragm made of a material capable of absorbing and giving off heat and situated a little above the basal edges of the box, a roof or top of a form rising toward the middle to allow for the uniform distribution

of heat, and means for supplying heat to the interior of the box.

2. An apparatus for drying and heating the surface of, or material laid on, a road or road foundation, comprising a shallow box 70 inclosed on all sides, having an open bottom, a perforated diaphragm made of a material capable of absorbing and giving off heat and situated a little above the basal edges of the box, a roof or top of a form rising toward the middle to allow for the uniform distribution of heat, and means for supplying heat to the interior of the box. 75

3. An apparatus for drying and heating the surface of, or material laid on a road or 80 road foundation, comprising a shallow box inclosed on all sides, having an open bottom, a roof or top of a form rising toward the middle to allow for the uniform distribution of heat, means for supplying heat to the interior of said top, and a diaphragm made of a material capable of absorbing and giving off heat and situated at the junction of the sides of the box and the top. 85

4. An apparatus for drying and heating 90 the surface of, or material laid on a road or road foundation, comprising a shallow box inclosed on all sides, having an open bottom, a low roof or top of truncated pyramidal form, means for supplying heat to the interior of the said top, and a diaphragm made of a material capable of absorbing and giving off heat and situated at the junction of the sides of the box and the top. 95

5. An apparatus for drying and heating 100 the surface of, or material laid on a road or road foundation, comprising a shallow box inclosed on all sides, having an open bottom, a low roof or top of truncated pyramidal form, means for supplying heat to the interior of the said top and a perforated diaphragm made of a material capable of absorbing and giving off heat and situated at the junction of the sides of the box and the top. 105

6. An apparatus for drying and heating the surface of, or material laid on a road or road foundation, comprising a shallow box inclosed on all sides, having an open bottom, a low roof or top of truncated pyramidal form, means for supplying heat to the interior of said top, a rack at the junction of the top and sides and a plurality of plates forming a diaphragm mounted on said rack, said plates consisting of material capable of absorbing and giving off heat, and means for securing said plates to said rack. 115

7. An apparatus for drying and heating the surface of, or material laid on a road or road foundation, comprising a shallow box 120 inclosed on all sides, having an open bottom, a low roof or top of truncated pyramidal form, a plurality of openings in the said top for the insertion of a plurality of blow lamps, a plurality of brackets adjacent to 125

said openings, each of which brackets is adapted to serve as a support for a blow lamp, a pipe in the top centrally arranged projecting into the top, closed at the bottom and laterally perforated for the supply of hot fluid to the interior of the top, and a diaphragm at the junction of the top and sides,

said diaphragm consisting of material capable of absorbing and giving off heat.

WILLIAM BLACKWELL COWELL.
